(57) **CLAIM**

I claim the ornamental design for a remote control, as shown and described.

DESCRIPTION

FIG. 1 is a front view of the remote control of the present invention, in accordance with a first embodiment of the invention;

FIG. 2 is a back view of the remote control of FIG. 1;
FIG. 3 is a right side view of the remote control of FIG. 1;
FIG. 4 is a left side view of the remote control of FIG. 1;
FIG. 5 is a top view of the remote control of FIG. 1;
FIG. 6 is a bottom view of the remote control of FIG. 1; and,
FIG. 7 is a perspective front view of the remote control of FIG. 1.
